Primary Examiner — Karen E Eldridge Powers**CLAIM**

(57) The ornamental design for a baseball glove shell, as shown and described.

DESCRIPTION

FIG. 1 is a front perspective view of the baseball glove shell showing my new design; and,

FIG. 2 is a rear perspective view of the baseball glove shell showing my new design.

The features shown in broken lines in the drawings illustrate those portions of the article to which the design is applied that form no part of the claim.
